(57) **CLAIM**

The ornamental design for a dental imaging attachment for a smartphone, as shown and described.

DESCRIPTION

FIG. 1 is a top perspective view of a dental imaging attachment for a smartphone in accordance with the present invention;

FIG. 2 is a back elevation view thereof;

FIG. 3 is a front elevation view thereof;

FIG. 4 is a right side elevation view thereof;

FIG. 5 is a left side elevation view thereof;

FIG. 6 is a bottom plan view thereof;

FIG. 7 is a top plan view thereof; and,

FIG. 8 is a bottom perspective view thereof.

The broken lines shown in the drawings depict portions of the dental imaging attachment for a smartphone that form no part of the claimed design.

1 Claim, 8 Drawing Sheets
